HEATER CASING

Robert L. Miller, Centralia, Ill., assignor to Lear Siegler,
Inc., Centralia, Ill., a corporation of Delaware

Filed Jan. 20, 1964, Ser. No. 78,252

Term of patent 14 years

(Cl. D81—10)

Fig. 1.

Fig. 2.

Fig. 3.

Fig. 4.

FIGURE 1 is a perspective view of a heater casing showing my new design;

FIGURE 2 is a top plan view;

FIGURE 3 is a side elevational view taken from the left side of FIGURE 1; and

FIGURE 4 is a side elevational view taken from the right side of FIGURE 1.

The rear and bottom portions of the casing are open and substantially plain.

I claim:

The ornamental design for a heater casing substantially as shown and described.
